(57) **CLAIM**

The ornamental design for a powered brush handle, brush, charger, and cap, as shown and described.

DESCRIPTION

FIG. 1 is a top front right perspective view of a powered brush handle, brush, charger, and cap in accordance with our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof;

FIG. 8 is a top front right perspective view thereof with the cap removed for convenience; and,

FIG. 9 is an exploded top front right perspective view thereof.

The broken lines immediately adjacent the shaded areas represent the bounds of the claimed design while all other broken lines are included for the purpose of illustrating portions of the powered brush handle with brush, charger and cap; the broken lines form no part of the claimed design.
